UNITED STATES PATENT OFFICE.

HARRIS H. HAYDEN, OF NEW YORK, N. Y., ASSIGNOR TO THE LAMSON CASH RAILWAY COMPANY, OF BOSTON, MASSACHUSETTS.

CARRIER FOR STORE-SERVICE APPARATUS.

SPECIFICATION forming part of Letters Patent No. 280,468, dated July 3, 1883.

Application filed May 18, 1883. (No model.)

To all whom it may concern:

Be it known that I, HARRIS H. HAYDEN, of the city, county, and State of New York, have invented certain Improvements in Carriers for 5 Store-Service Apparatus, of which the following is a specification.

My invention consists, mainly, in certain improvements in carriers for store-service apparatus, whereby I am enabled to facilitate the 10 insertion and removal of the goods to be carried without the dangers heretofore incident to the removal of the carriers from the ways, the said improvements being hereinafter fully described, and illustrated in the accompanying 15 drawings, in which—

Figure 1 is a side view of a carrier illustrating my improvements; Fig. 2, an end view. Fig. 3 is a part sectional elevation, showing a 20 device for removing the receptacle of a carrier and a stand for supporting the same.

The carrier consists of a body or frame, *f*, provided with one or more friction-wheels, adapted to run upon the way *A*, of any suitable construction, and a receptacle, *h*, connected 25 in any suitable manner with the frame *f*, so as to be readily detachable therefrom. As shown, the frame *f* extends beneath or embraces the wire constituting the way *A*, so that the body of a carrier is undetachable from the way. The 30 frame, however, may be differently constructed, and may be provided with loops embracing the way, or may in any other suitable manner be prevented from being withdrawn from the way while capable of ready movement thereon.

Any suitable connection may be made between the receptacle *h* and the frame of the carrier. As shown, the carrier has a projection, *e*, with pins *d* at the sides, with which engage hooks *g* upon the frame of the receptacle 40 *h*, which may therefore be detached by lifting it slightly and then moving it to one side, leaving the frame upon the way.

The receptacle may be constructed either for the reception of parcels or to hold merely the 45 money or the books of the salesmen. As shown, it is intended for the reception of goods, and consists of a rectangular frame or bail, *j*, arranged vertically, and a horizontal frame, *m*, connected thereto and supporting a flexible 50 bag, *p*, of netting, fabric, or other material;

and this material may be elastic or extensible, so as to permit the introduction of articles of different sizes. By the combination of the frames *m*, *j*, I secure considerable stiffness, without undue increase in weight—a stiffness which 55 is especially desirable when, as shown, the carrier is provided with a pendent handle, *n*, which may be used to raise or lower the receptacle, or, in cases where the receptacle and frame are permanently connected, as a means for taking the carrier readily from the track. The pendent handle also serves as a means of propelling the carrier from below.

When the ways are at a considerable distance above the floor, it is desirable to provide means 65 whereby the receptacle may be removed without the operator necessarily taking an elevated position. For this purpose I employ a supplemental handle, *F*, having a socket, *x*, at the upper end, to receive the handle *n*, which in 70 such case may be in the form of a pin or projection, as shown in Fig. 3. By means of this handle the receptacle may be readily reached from below and lifted from its supports upon the carrier-frame, or elevated and connected 75 thereto. The top of the handle *F* may have one or more notches, *y*, to receive ribs *r* upon the receptacle. This prevents the carrier or receptacle from turning round on the handle, and permits the attendant to manipulate the 80 parts so as to facilitate the attachment and detachment of the same.

The operations of the apparatus may be greatly facilitated by providing a means for holding the receptacles when not in use. For 85 this purpose I employ a frame, *H*, secured to the counter, or in any other suitable position, and provided with a socket for receiving the handle *F*, or otherwise constructed to afford a suitable support. This frame *H* may be in the 90 form of a standard or a bracket, for attachment to the wall or shelving.

To prevent the accidents resulting from the wheels of the carrier slipping from the way, and the jamming of the latter between the sides of 95 the wheels and the frame, I provide the carrier with fingers *i*, extending upward at opposite sides of the way and diverging to form a V-shaped notch, which effectually prevents the wheels from slipping to one side of the way, 100

As shown, these fingers are formed by bending up the notched ends of a strip, *w'*, extending beneath the wheels.

It is obvious that the stand for the reception 5 of the supplemental handle may, if desired, be used without the latter, if the carrier or the handle or projection on the same is so shaped as to fit the stand.

As shown, the portion 2 of the frame is heavy 10 enough to counterbalance the wheels and maintain the body of the carrier in an upright position, where the receptacle is detached. It is advisable, however, in many instances to hold the body positively in place. Different 15 supports may be used for this purpose—for instance, a finger, *w*, extending from an arm or hanger, *I*, and catching in a loop, *u*, on the carrier; or the carrier may run between fingers or stops at opposite sides.

20 Without limiting myself to the precise construction of parts set forth, I claim—

1. The combination, with the way of a store-service apparatus, of a carrier having a body moving upon the way and permanently connected therewith, and a receptacle detachably connected with the body of the carrier, substantially as set forth.

2. A carrier for store-service apparatus, consisting of a body adapted to move upon the 25 way, and a receptacle connected detachably to the body, substantially as specified.

3. The combination, in the receptacle of a store-service carrier, of a vertical frame, *j*, and a horizontal frame, *m*, connected together and supporting a flexible bag, *p*, substantially as 35 set forth.

4. The combination, with a store-service carrier, of a pendent handle extending below the receptacle, substantially as specified.

5. The combination, with a store-service carrier having a pendent handle, of a supplemental handle provided with a socket, for the purpose set forth.

6. The frame of a store-service carrier, provided with projections extending upward upon 45 opposite sides of the way, for the purpose specified.

7. A frame, *H*, adapted for attachment to a counter or support, and constructed as a support for the carrier or receptacle, substantially 50 as set forth.

8. The combination, with the way and the carrier, having a detachable receptacle, of a support for the body of the carrier, substantially as set forth.

In testimony whereof I have signed my name to this specification in the presence of two subscribing witnesses.

HARRIS H. HAYDEN.
